DEEP WELL ELEVATOR

Filed April 13, 1922

INVENTOR:
JOHN GRANT,
BY: Otto H. Kueger,
his Atty.

UNITED STATES PATENT OFFICE.

JOHN GRANT, OF LOS ANGELES, CALIFORNIA, ASSIGNOR, BY MESNE ASSIGNMENTS, TO BYRON JACKSON PUMP CO., OF WEST BERKELEY, CALIFORNIA, A CORPORATION OF DELAWARE.

DEEP-WELL ELEVATOR.

Application filed April 13, 1922. Serial No. 552,265.

This invention relates to devices used for handling tools and materials in connection with oil and other wells.

One of the objects of this invention is to 5 provide an elevator with locking means to prevent any accidental disengaging of any parts of the device.

Another object is to provide locking means 10 for the link members of the device to prevent the link members from disengaging from the hoisting hook, to which the device is normally attached, being at the same time suitable and useful for jarring operations.

Another object is to provide closing and 15 locking means on the ends of the body member of the device which can easily be swung out of the way of the disengaging link members, tending to save time in handling the device, there being no bolts to be unscrewed 20 when the link members are to be disengaged from the body of the device.

Another object is to provide latch-members 25 for locking a movably disposed portion of the body of the device to the main portion of the body.

Another object is to provide locking means for the body latch.

Other objects will appear from the following description and appended claims as well 30 as from the accompanying drawing, in which—

Fig. 1 is a perspective illustration of the device, the link members being broken off short above the body member.

35 Fig. 2 is a detail top plan view of the latch mechanism for locking the movably attached portion to the main portion of the body.

Fig. 3 is a side elevation of the locking mechanism of latch mechanism on the body, 40 the locking mechanism forming a safety means for the latch mechanism.

Fig. 4 is a top plan view of a slightly modified form of the latch mechanism, with locking mechanism.

45 Fig. 5 is a fragmentary side elevation of a hoisting hook, with the two upper ends of the link members in proper engaging position.

Fig. 6 is a fragmentary front elevation of a 50 link member, illustrating engaging stops on the link.

Fig. 7 is a fragmentary front elevation of a link, illustrating a slightly modified form of stop for the link.

Fig. 8 is a cross section on line 8—8 of 55 Fig. 6.

Fig. 9 is a fragmentary top plan view of the body portion of the elevator, illustrating the closing attachment for the link-engaging hooks of the body.

Fig. 10 is a side elevation of a slightly modified form of latching means for the door lock. 60

Fig. 11 is a fragmentary side elevation of a well casing, illustrating, in reduced scale, the coring of the body.

Devices of this type are normally loosely 65 engaged around a well casing, pipe, or tool, under certain shouldered portions of the same. In Fig. 11 is, for instance, shown a well casing 12 with a coupling collar 13, under which the elevator body 14 is engaged, the 70 upper face 15 of the elevator body 14 shouldering against the lower edge of the coupling collar 13.

The supporting links 16 of such an elevator are normally attached to the large hook 75 of the lifting mechanism of a well rig, a portion of such a hook being indicated at 17 in Fig. 5. Such a hook is normally open and of such a shape that the links easily disengage 80 from the hook. A disengagement may under some conditions be very dangerous to the operators and occasion loss by dropping the load. It is therefore desirable to design and shape the links so that they will not easily disengage from the hook. In Figs. 5, 6 and 85

8, cross pieces 18 are clamped over the sides of the link 16, and held in position by the bolts 19. These clamp-like stops can be adjusted to come so close to the hook that the link cannot disengage from the hook except 90 when swung upwardly for that very purpose, and accidental disengaging can positively be avoided in this manner. Such a close engagement of the hook with the links allows also a jarring similar to the operations otherwise requiring special so-called jars. In the 95

slightly modified form illustrated in Fig. 7, the link is provided with a welded-in cross piece 20.

The supporting links are normally engaged 100 with the lugs 22 of the body 21 of the elevator, as illustrated in Fig. 1. The lower ends of the links are therefore also preferably provided with protecting cross pieces 18 likewise assisting in the jarring operation above 105 mentioned.

The body is provided with engaging lugs 22, to which the links are engaged. One side of the body is open, as indicated between the points 23 and 24. A door 25 is in operative 110

connection with the body for closing the open side of the body.

In handling well casing, tools, and other objects with an elevator in connection with a well rig, it is essential that such an elevator can be opened and closed in the shortest time possible, to avoid loss of time in lifting and lowering such objects. At the same time, the elevator must be absolutely securely locked 10 at the moment it is applied to such objects.

The latch members 26 are pivotally engaged with the door, as indicated at 27, near the inner engaging face 28 of the door, so as to project towards the outer surface of the 15 door. The engaging shoulder 29 of the latch 26 is made to engage with the engaging shoulder 30 in the body 21 to produce a wedging action increasing in effectiveness as the door is subjected to increased outward pressure. Springs 31 control the movements of 20 the latch members 26, so that the handle portion of the latch members is normally pressed outwardly by the action of the springs. A large and convenient handle portion is embodied in the latch mechanism, as indicated at 32, connecting the spaced upper and lower parts of the two latch members illustrated in 25 Fig. 1. A locking pawl 33 is pivotally engaged to the door as indicated at 34, by which the latch member can be locked in engaged 30 position as well as in disengaged position.

In Fig. 2, the automatic locking of the latch is illustrated in top plan view, the latch being shown in disengaged position in full 35 lines, while the locking position is indicated in dotted lines, indicated at 35. The locking pawl is provided with the lug 36 projecting upwardly, coming in front of the latch member when the latch member is in disengaged 40 position while in rear of the latch member when the latch member is in locking position.

It is, however, not absolutely necessary to lock the latch against movement when in disengaged position. The slightly modified 45 form illustrated in Fig. 10 is merely in form of a drop-pawl, the pawl 37 being pivotally engaged at 38 to the front near the upper edge of the door 25. The pawl is provided with the shoulder 39 to engage behind the latch 50 in the locking position of the latch, while no provision is made for locking the latch in disengaged position. The pawl 37 is furthermore arranged and made of a length to extend with its free end 40 inwardly beyond 55 the inner engaging face 28 of the door, so that, on a closing of the door against a well casing, the end 40 hits the casing and is thereby caused to fall into engaging position, onto the latch, with the shoulder 39 behind the latch, 60 thereby locking the latch and door securely within the body 21.

The pawl, either the form 33 or the form 37, can easily be unlocked by the operator when taking hold of the handle 32 by a movement of the thumb or finger of the operator. 65

The form of pawl illustrated in Figs. 1, 2 and 4 is preferably spring-operated, as indicated at 41 in Fig. 3; while the pawl, illustrated in Fig. 10 is operative by its own weight. 70

A slightly modified form of latch member is illustrated in Fig. 4, instead of arranging the pivot point of the latch member near the inner face of the door as illustrated in Figs. 1 and 2, the pivot of this latch member is near 75 the outside of the door 25, as indicated at 42. Instead of bracing against the body of the elevator, as illustrated in Figs. 1 and 2, this latch member is provided with a hook-like engaging member 43 to engage behind a co-acting 80 engaging member on the body, as indicated at 4. This latch member is also spring-controlled, as indicated at 45.

Both forms of latch members are arranged so that the door 25 may be swung or moved 85 into closing position without requiring an operation of the latch members, that is, the front faces 46 and 47 of the latch members are beveled suitably in order to allow the latch members with the door to move into closing 90 position within the body 21.

The body 21 of the elevator is furthermore provided with swiveling locking members 48 for holding the link-engaging hooks 22 of the body closed. These locking members 95 reach over the tops of the link-hooks, and are pivotally engaged with the base plate 49 of the elevator, as indicated at 50. In Fig. 9, one of these locking members is illustrated in top plan view, the distance from the center of the pivot 50 to the end 51 of the base plate being greater than the distance from the center of the pivot to the side edge 52 of the base, so that the upper edge 53 of the locking member becomes spaced from the link-hooks to an 100 extent that a link can easily be moved in and out, the space being indicated in dotted lines at 54.

The inner face of the body 21 is preferably cored out to form an engaging face only near 110 the upper edge, as indicated at 55 in Figs. 1 and 11, the larger portion of the body being cored out to such an extent as not to engage when applied to a well casing, tool, or other articles handled in wells, facilitating application of the elevator to the work by decreasing the inner contacting surface. Such a coring serves furthermore to facilitate a handling of such an elevator, in the first place for the reason that the elevator itself is normally of 115 heavy type, and for another reason that the well casing or tools to be engaged by the elevator are also heavy.

In lowering the elevator to the floor, it does not always align properly with a casing, lying on the floor or ground and to be lifted or engaged by the elevator. The coring, indicated at 56 in Fig. 11, facilitates the applying of an elevator to a casing while the elevator may be in an inclined position to the casing as 120 125 130

indicated at 57 in dotted lines. The elevator can be applied and closed, and, in lifting the elevator, the upper edge and engaging face 55 of the elevator will engage under the coupling of the casing as the elevator slides along the casing.

Having thus described my invention, I claim:

1. In an elevator, a body, a door operatively engaged to the body at one end, latching means pivotally engaged to the free end of the door with the pivot near the inner cylindrical engaging face of the body and door so that the engaging end of the latching means projects outwardly from the axis of the elevator, an engaging lug on the body to engage over the engaging end of the latching means, and means for automatically maintaining the latching means in engaging position and adapted to yield to manual manipulations.
2. In an elevator, a body, a door operatively engaged to the body at one end, latching means pivotally engaged to the free end of the door with the pivot near the inner engaging face of the body and door so that the engaging end of the latching means projects outwardly from the axis of the elevator, means on the body for engaging with the engaging end of the latching means, means for automatically maintaining the latching means in engaging position and adapted to yield to manual manipulations, and a latching pawl on the door projecting towards the first-named latching means for holding the first-named latching means in interlocking position in relation to the body and door and adapted to yield to manual manipulation.

In testimony that I claim the foregoing as my invention I have signed my name.

JOHN GRANT.
